UNITED STATES PATENT OFFICE.

GEORGE H. NOLL, OF NEW YORK, N. Y.

CLOTHES-LINE CLAMP.

1,074,736.

Specification of Letters Patent.

Patented Oct. 7, 1913.

Application filed April 23, 1912. Serial No. 692,722.

To all whom it may concern:

Be it known that I, GEORGE H. NOLL, a citizen of the United States, residing in the borough of Brooklyn, county of Kings, 5 city and State of New York, have invented certain new and useful Improvements in Clothes-Line Clamps, of which the following is a specification.

This invention relates to clothes line 10 clamps or the like, and is an improvement upon my invention set forth in my U. S. application, Serial No. 607,949.

In the use of my aforesaid invention it has been found that the rope is frequently 15 so tightly clamped by the device that it is difficult to release its hold on the rope so as to loosen the rope. This frequently arises from contraction of the rope on drying after having been wet. By the present 20 invention a structure is provided which may be easily manipulated to release a rope and with which the manipulation can be carried out with one hand, the other hand being free to grasp the free end of the rope so as to 25 control the slack.

Other features of improvement will be found in details of construction hereinafter described.

Referring to the drawing, Figure 1 illustrates the device applied to a clothes line. Fig. 2 is an enlarged side elevation of the device in position on a line, partly in section. Fig. 3 illustrates the manner in which the device is grasped to release a line.

35 As illustrated, the fastener is represented as made in two parts A and B, between which a rope C is adapted to pass and be clamped, the rope being attached to one of the parts and passing over pulleys at two 40 points of support. The part A is provided with a grooved inner face a which forms a runway for the rope, and with an eye or opening a^1 at the upper end of the runway, through which the rope passes. The part 45 A is also provided with a pair of ears a^2 on either side of the inner face thereof, between which ears the part B is pivotally mounted on a pin b , for instance. The lower end or jaw b^1 of the part B and the lower 50 end of the part A form the parts between which the rope is clamped, and the end b^1 of the part B is preferably provided with downwardly projecting teeth b^2 in order that it may secure a firmer hold on the rope. 55 The end b^1 of the part B and the inner

face a of the part A are also preferably convexly curved so that a combined pressing and wedging action is produced on the rope by the lower ends of the parts A and B when force is applied to the upper ends thereof 60 tending to move them apart, as when tension is applied to the clothes line to tighten it. The upper end of the part B is formed with an eye b^3 or similar device to which the clothes line is attached. The part A is provided with a prolongation or arm a^3 , this prolongation preferably extending inwardly 65 over the upper end of the part B. By grasping the prolongation a^3 and the upper end or eye b^3 of the part B between the fingers 70 and thumb, as illustrated in Fig. 3, the device may be conveniently grasped and a leverage obtained by which the jaws may be more easily moved apart to release the 75 rope clamped between them, and the use of the device thereby facilitated.

It is of course to be understood that modifications may be made in the structure illustrated and described without departing from the spirit of the invention.

What is claimed is:—

1. A clothes-line fastener comprising two arms, pivoted together between their ends, and adapted to clamp a rope between them, the ends of said arms on one side of the pivot 85 diverging beyond the pivoted point, means on the divergent end of one of said arms for attaching a rope, means on the other of said divergent arms, substantially opposite said rope-attaching means, through which the 90 rope is adapted to run, one of said arms having an elbow extension thereon extending over and above the opposite end of the opposite arm, whereby the elbow extension and opposite end of the opposite arm are 95 adapted to be grasped between the thumb and fingers and pressed together to force apart the opposite ends of the arms between which the rope is gripped and loosen the grip of the arms upon said rope.

2. A clothes-line fastener comprising two arms pivoted together between their ends, and adapted to clamp a rope between them, one of said arms being formed on a convex 105 curve on its inner side and forming a runway for the rope, and diverging at one end from the opposite end of the opposite arm, said convex arm having at its divergent end an eye through which a rope is adapted to run, and said opposite arm having opposite 110

said eye means for attaching thereto the end of a rope, said convex arm also having an elbow extension thereon extending over and above the opposite end of the opposite arm, whereby the elbow extension and opposite end of the opposite arm are adapted to be grasped between the thumb and fingers and pressed together to force apart the opposite ends of the arms between which the rope is

gripped and loosen the grip of the arms 10 upon said rope.

In witness whereof, I have hereunto signed my name in the presence of two subscribing witnesses.

GEORGE H. NOLL.
